Specification for Design.

Patented July 13, 1915.

Application filed May 14, 1915. Serial No. 28,220. Term of patent 3½ years.

To all whom it may concern:

Be it known that I, EMILE J. OZANNE, a subject of the King of Great Britain, residing at Manhattan, in the city of New York, in the county of New York and State of New York, have invented a certain new, original, and ornamental Design for a Lace Fabric, of which the following is a specification.

In the accompanying drawing which

forms a part of this specification, the figure is a front elevation of a lace fabric embodying my new design.

I claim:

The ornamental design for a lace fabric, as shown.

EMILE J. OZANNE.
